HENRY B. SUTTER AND KIRK GRUBER HASELTINE, OF SPRINGFIELD, MISSOURI

FRUIT BASKET PACKING DEVICE

Application filed December 27, 1929. Serial No. 416,908.

The invention relates to packing devices for fruit baskets and has for its object to provide a device of this character comprising a cylindrical tub section having spaced stops extending inwardly adjacent the bottom thereof, and on which a concaved facing plate rests, and to provide means whereby a fruit basket may be received on the upper end of the tub in inverted position for the reception of fruit packed in the tub upon upward movement of the facing plate within the tub.

A further object is to taper the upper end of the tub so that the same will receive the fruit basket in inverted position and to proportion the facing plate whereby upon downward movement of the facing plate, it will pass through the upper open end of the tub and be received in the basket.

A further object is to provide one side of the facing plate with spring catches adapted to spring into hooked engagement with the inner ring of the basket for holding one side of the plate when moving the basket from the tapered end of the tub.

A further object is to provide the inner concaved side of the facing plate with a plurality of concentric rings, preferably formed from fibrous material, stitched between layers of fabric, thereby forming concentric grooves in which the facing fruit may be arranged, and at the same time preventing bruising of the fruit when poured into the tub onto the facing plate.

A further object is to form the facing plate stop lugs from bracket members secured to opposite sides of the tub and having portions inclining downwardly and inwardly through apertures in the wall of the tub, and inclining downwardly and outwardly into engagement with the periphery of the tub, adjacent the tub bead for rigidly bracing the lugs.

A further object is to provide an ejector stand for the facing plate comprising an annular member adapted to engage the under convex side of the facing plate, in a manner whereby when the tub is packed, the tub and facing plate will center themselves, and means for securing the stand to a support or table.

With the above and other objects in view the invention resides in the combination and

arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a perspective view of the packing device, showing the same after the tub filling operation, and in position on the ejector stand.

Figure 2 is a perspective view of the ejector stand, showing the same supported on a table.

Figure 3 is a top plan view of the facing plate.

Figure 4 is a vertical transverse sectional view through the basket filling device.

Figure 5 is a horizontal sectional view taken on line 5—5 of Figure 4.

Figure 6 is an enlarged vertical transverse sectional view through one side of the facing plate showing the facing channel applied thereto.

Referring to the drawings, the numeral 1 designates the tub, which is preferably cylindrically shaped, as shown, and has its lower end provided with a reinforcing bead 2, and its upper end with a tapered portion 3, which tapered portion 3 is adapted to engage within the basket 4 to be filled, upon a reversing operation. Tapered portion 3 of the tub engages the inner periphery of the inner band 5 of the basket, as clearly shown in Figure 4.

In operation, the tub 1 is placed on a table 6 with its bead 2 downwardly disposed, and with the concave facing plate 6 in the tub, and on which plate, fruit to be packed and forced into the basket 4 is placed.

Secured to opposite sides of the tub 1 by means of rivets 7 are vertically disposed brace arms 8 and 9. The upper ends of the arms 8 terminate in outwardly extending handle members 10 adapted to be grasped by the operator during the handling of the device. The arms are omitted from the brace arms 9 so they will not be in the way of the operator. Brace arms 8 and 9 extend down-

wardly and terminate in inwardly extending arms 11, which extend through apertures 12 in the sides of the tub, and to positions within the inner diameter of the upper tapered end 3 of the tub where they will be engaged by the under convex side of the facing plate 6 for limiting the downward movement of the facing plate. Arms 11 terminate in downwardly and outwardly extending arms 13, which engage the inner periphery of the tub adjacent the reinforcing bead 2, therefore it will be seen that the arms are thoroughly braced for supporting the weight of the facing plate and fruit therein, which is built up to a position adjacent the upper end of the tub.

Disposed in the concaved upper side of the facing plate is a pad 14, preferably formed from two layers of fabric 15, between which are placed rings 16, which may be any number, however for purposes of illustration two are shown. The rings 16 may be formed from any material, for instance, rope, rubber or leather and held in concentric relation by means of stitching 17, therefore it will be seen when fruit is dumped into the tub, when the tub is on a table or other support, the fruit will not be injured, that is, the facing fruit 18, indicated in dotted lines in Figure 3, and which fruit is arranged symmetrically and concentrically between the rings on the pad 14, as shown in dotted lines in Figure 3. The outer marginal edge of plate and pad is preferably held within a clamping ring 19.

In operation the tub 1 is placed on a table with its bead 2 resting on the table, then the facing plate 6 with its pad 14 is placed in the tub resting on the inwardly inclined stop arms 11 adjacent the bottom of the tub. After placing the facing plate 6 in position, the facing fruit 18 is arranged between the concentric rings of the pad and the desired amount of fruit built up in the tub. After the fruit is arranged the operator grasps the oppositely extending handles 10 and lifts the tub and places the same on the annular member 20 of the stand 21, and it will be noted that by providing the stand 21 with the annular member 20 of smaller diameter than the facing plate 6, when the convexed under side of the facing plate engages the ring 20, the facing plate will have a tendency to center on the stand incident to the weight of material thereon. The basket 4 may then be placed on the tapered end 3 of the tub and the operator forces the basket downwardly, which action will force the tub 1 downwardly overcoming the frictional holding of the tub by the fruit therein with the ejector stand 21 holding the facing plate against downward movement. This operation will cause the fruit in the tub 1 to be forced into the basket 4, and as the facing plate 6 is smaller in diameter than the open end of the tapered

portion 3 of the tub, said facing plate will pass partially into the basket 3 where its spring hooks 22, to one side thereof, will hook over the basket band 3. At this point the operator grasps the basket, forces the same upwardly at the nonhook side until he can grip the free side of the facing plate and then he turns the basket with its contents over so that its bottom 23 is placed on the table, and after which operation, the facing plate is removed from the basket mouth, and is again placed in the tub for the next operation.

From the above it will be seen that a basket filling apparatus is provided, which is simple in construction, the parts reduced to a minimum, and one wherein the filling operation is rapid, and the facing fruit arranged in an artistic manner, thereby increasing the saleability.

The invention having been set forth what is claimed as new and useful is:—

1. A fruit basket filling device comprising a cylindrical tub, the upper end of said tub being restricted and adapted to receive thereon the inner hoop of an open end of an inverted fruit basket, a removable ejector bottom in the tub and vertically movable in the tub and through the upper restricted end of the tub and hook means carried by the bottom and cooperating with the inner hoop of the fruit basket for holding the bottom in relation to the basket while removing the basket from the tub.

2. A fruit basket filling device comprising a tub having its upper end open, means for supporting a receptacle on the upper end of the tub, a vertically movable ejector bottom in said tub, brace bars secured to opposite sides of the tub, said brace bars having their lower ends extending downwardly and inwardly through the wall of the tub and underlying the ejector bottom, said downwardly and inwardly extending portions of the bars terminating in downwardly and outwardly extending portions engaging the tub, and handle members carried by said tub.

3. A fruit basket filling device comprising a tub, means for receiving and supporting a basket on the upper end of said tub in an inverted position, a removable ejector bottom in the tub and vertically movable through the upper end of the tub and interengaging means carried by said bottom and cooperating with the basket for holding the bottom in relation to the basket while removing the basket from the tub.

4. A fruit basket filling device comprising a tub, means carried by the upper end of the tub for receiving the open end of a basket and supporting the same in an inserted position on the tub, a removable ejector bottom in the tub and vertically movable therethrough and outwardly movable interengaging members carried by the bottom and cooperating with

the basket for attaching the bottom thereto and maintaining the same in relation to the basket when the basket is removed from the tub.

- 5 5. A fruit basket filling device comprising a tub, the upper end of said tub being open and adapted to receive thereon in an inverted position a fruit basket, an ejector bottom in the tub and vertically movable therethrough and spring actuated interengaging means carried by the bottom and adapted to interengage with the basket for holding said bottom in relation to the basket when the basket is removed from the tub.
- 10 6. The combination with a fruit basket filling device comprising a tub having means for supporting a basket thereon in inverted position, a removable bottom vertically movable through the tub, of interengaging means carried by the bottom and cooperating with the basket whereby when said basket is removed from the tub said bottom is attached to the basket.
